PLASTIC SWIMMING POOL

William Scott Eubanks, Jr., Dade County, Fla., assignor to
W. R. Chance and Associates, Inc., Arlington County,
Va., a corporation of Delaware

Application April 20, 1956, Serial No. 41,144

Term of patent 14 years

(Cl. D34—5)

Fig. 1

Fig. 2

Fig. 3

Fig. 5

Fig. 4

Fig. 8

Fig. 7.

Fig. 6.

I claim:

The ornamental design for a plastic swimming pool, as shown.
